UNITED STATES PATENT OFFICE

HARRY SLOAN, OF FOX POINT, WISCONSIN, ASSIGNOR TO THE VILTER MANUFACTURING COMPANY, OF MILWAUKEE, WISCONSIN, A CORPORATION OF WISCONSIN

REFRIGERATING APPARATUS

Application filed July 30, 1931. Serial No. 553,978.

The present invention relates in general to improvements in the art of separating non-condensable gases from condensable vapors, and relates more specifically to an improved method of and apparatus for purging refrigerating systems or the like for the removal of air and other objectionable gases.

An object of the invention is to provide improved purging apparatus which is simple and compact in construction and which is moreover highly efficient in operation.

The presence of air and other non-condensable gases in refrigerating systems, is extremely objectionable since it increases the condenser pressure in proportion to the partial pressures of the non-condensable air and other gases. Such increase in condenser pressure results in increased power requirements for actuating the compressor, and the presence of non-condensable gases such as air also undesirably reduces the surface available for condensing the refrigerant. The existence of such non-condensable gases in the system therefore materially reduces the efficiency thereof, and hence makes their elimination extremely desirable.

The non-condensable gas ordinarily present in greatest quantities, is air which is introduced into the refrigerating system when making repairs, and also through leaky joints and stuffing boxes when a vacuous condition is established within the system. Air is considerably heavier than ammonia vapor and the like, and will therefore accumulate in the condenser and in the liquid ammonia receiver, above the level of the liquid refrigerant. While it has heretofore been customary to remove such non-condensable gases from cooling systems by means of so-called gas separators, these prior devices are quite complicated and correspondingly high priced, and they are moreover apt to become out of order unless given proper attention at frequent intervals.

It is also customary in many refrigerating installations, to provide a small liquid ammonia line for injecting liquid into the suction line of the pump close to the compressor cylinder. Such a liquid conducting line is used when operating at low suction pressures

under which conditions the compressor operates upon highly heated gases. The same condition also exists if the return gas to the compressor is highly superheated, whereupon liquid is injected into the cylinder in order to obtain safer operating temperatures.

It is a more specific object of the present invention to provide an effective purge device especially adapted for use in refrigerating systems, which may be manufactured and installed at minimum cost.

Another object of the invention is to provide a gas separator which will effectively separate non-condensable gases from condensable vapors such as refrigerant, and which will also effect subsequent delivery of the former from the separating chamber.

Another specific object of the invention is to provide an improved purge drum, which when once installed is not subject to disorder and therefore will require minimum attention.

A further specific object of the invention is to provide a combined purging appliance and return pipe communicating with the suction line of the compressor, so that the purging device and the return line may be used either independently or otherwise, as desired.

These and other objects and advantages will be apparent from the following detailed description.

A clear conception of one embodiment of the invention and of the mode of constructing and of operating urge apparatus built in accordance therewith, may be had by referring to the drawing accompanying and forming a part of this specification in which like reference characters designate the same or similar parts in the several views:

Fig. 1 is a diagrammatic disclosure of a typical refrigerating system having one form of the improved purge apparatus applied therein; and

Fig. 2 is an enlarged fragmentary sectional view through the receiver and purge tank of the system.

The typical refrigerating system shown in Fig. 1 comprises in general, a compressor 5 having suction and discharge lines 6, 7 respectively; an evaporator 8 communicating

with the suction line 6 of the compressor; a condenser 9 communicating with the discharge line 7 of the compressor; and a liquid refrigerant receiver 10 communicating with the evaporator 8 and with the condenser 9 to complete the system.

The compressor 5 may be either of the reciprocating or of the rotary type, and the suction and discharge lines 6, 7 thereof are preferably provided with flow control valves 11, 12 respectively. The compressor suction line 6 is in direct communication with the delivery end of the evaporator 8, while the inlet end of the evaporator communicates with the lower portion of the receiver 10 through a pipe 13 having a flow control valve 14 therein. The compressor discharge line 7 is likewise in direct communication with the upper part of the space surrounding the heat transfer tubes 15 of the condenser 9, and the lower part of this space communicates with the upper portion of the receiver 10 through a pipe 16. The receiver 10 normally has liquid refrigerant 17 in the lower portion thereof, and a gas space 18 above the liquid refrigerant.

The improved purge device comprises an inner tubular casing 19 and an outer casing 20 surrounding and spaced from the inner casing 19 to form a jacket 21. The inner casing 19 may be formed of a length of pipe having its extreme ends sealed, and the outer casing 20 may likewise be formed of a somewhat shorter length of pipe of larger diameter. The outer and inner casings may be interconnected by welding or otherwise attaching tapered pieces 22 to the opposite ends of the casing 20 and to the adjacent outer portions of the casing 19. The jacket 21 is in open communication at the lower end portion thereof, with the gas space 18, through small holes 23, and the upper portion of the opposite end of the jacket is communicable with the outside atmosphere through a pipe 24 and a flow control valve 25. The purge unit is suspended within the receiver space 18, by means of pipes 26, 27 communicating with the opposite ends of the inner casing 19. The pipe 26 has a control valve 28 therein, and communicates directly with the pipe 13 which leads to the evaporator. The pipe 27 has a control valve 29 therein and communicates directly with the compressor inlet pipe 6. This piping arrangement is obviously such, that by manipulating the valves 28, 29, liquid refrigerant may be admitted in any desired quantities, from the receiver 10 to the compressor suction line 6, through the inner casing 19 of the purger.

During normal operation of the refrigerating system, the compressor 5 is functioning to withdraw liquid refrigerant 17 from the receiver 10 into the evaporator 8, and to remove the gaseous refrigerant generated in the evaporator through the suction line 6, the

control valves 11, 14 being adjusted to meet the requirements. The compressed gases are delivered past the valve 12 and through the discharge line 7 to the condenser 9 and the combined condensed refrigerant and non-condensable gases are eventually discharged from the condenser and delivered to the receiver 10 through the pipe 16. The non-condensable vapors accumulate in the receiver space 18, while the liquid refrigerant 17 accumulates below this space and is subsequently again passed through the heat transfer cycle.

The purging device operates as follows:— The valves 25, 28, 29 are opened thereby permitting a small quantity of liquid refrigerant to enter the inner casing 19 through the pipe 26. The refrigerant thus admitted, absorbs heat from the jacket 21 and is vaporized, the resultant vapor being removed through the pipe 27 by the compressor 5. The non-condensable gases and vapors which accumulate in the receiver space 18 are free to enter the jacket 21 through the openings 23, and pass lengthwise of the jacket toward the outlet pipe 24. Any condensable gases entering the jacket 21, are quickly condensed by the evaporation of liquid refrigerant within the inner casing 19, and the liquid resulting from this condensation returns to the receiver through the openings 23. The purge device may be operated either intermittently or continuously, and by closing the valve 25 and merely opening the valves 28, 29, liquid refrigerant may be injected directly into the compressor suction line 6 close to the compression cylinder when operating at low suction pressures or when the return gases are highly superheated.

From the foregoing description, it will be apparent that the present invention provides an extremely simple and compact purging device, which has proven highly efficient in actual commercial operation. The purger may moreover be utilized as a liquid injection line for the compressor for the purpose of enhancing the efficiency of operation of the system, and the use of the improvement is obviously not restricted to refrigerating systems. The casings of the purger, may be readily formed of standard pipe, and has no complicated parts which require periodic attention in order to maintain the same in effective operating condition.

It should be understood that it is not desired to limit the invention to the exact details of construction and to the precise mode of operation herein shown and described, for various modifications within the scope of the claims may occur to persons skilled in the art.

It is claimed and desired to secure by Letters Patent:

1. A purger comprising, an elongated horizontal inner casing, an outer tubular casing surrounding said inner casing to form a jacket embracing said inner casing intermediate

the ends of the latter, said outer casing having an opening at one end for admitting mixed gases to the lower portion of one end of said jacket, means for admitting refrigerant to an end of said inner casing beyond the adjacent end of said outer casing to cool said jacket and thereby condense some of the admitted gases, and means for effecting removal of the non-condensable gases from an upper portion of the opposite end of said jacket.

2. A purger comprising, an elongated horizontal inner casing, an outer tubular casing surrounding said inner casing to form a jacket embracing said inner casing intermediate the

15 ends of the latter, said outer casing having an opening at one end for admitting mixed gases to the lower portion of one end of said jacket, means for admitting refrigerant to an end of said inner casing beyond the adjacent end of said outer casing to cool said jacket and thereby condense some of the admitted gases, an outlet communicating with said inner casing beyond the opposite end of said outer casing, and means for effecting removal of the non-condensable gases from an upper portion of the opposite end of said jacket.

20 3. A purger comprising, an elongated horizontal cylindrical inner casing, an outer cylindrical casing surrounding said inner casing to form an annular jacket embracing said inner casing intermediate the ends of the latter, said outer casing having a plurality of openings at one end for admitting mixed gases to the lower portion of one end of said jacket, means for admitting refrigerant to an end of said inner casing beyond the adjacent end of said outer casing to cool said jacket and thereby condense some of the admitted gases, an outlet communicating with said inner casing beyond the opposite end of said outer casing, and means for effecting removal of the non-condensable gases from an upper portion of

45 the opposite end of said jacket.

In testimony whereof, I affix my signature.
HARRY SLOAN.
